United States Patent

Des. 239,828
Patented May 11, 1976

239,828

RETAIL FOOD MARKET

Howard Cooper, Suite 7707, John Hancock Center,
Chicago, Ill. 60611

Filed Apr. 1, 1970, Ser. No. 22,188

Term of patent 14 years

Int. Cl. D25—03

U.S. Cl. D25—8

Fig. 3.

Fig. 4.

FIG. 1 is a perspective view of a retail food market embodying my design;

FIG. 2 is a perspective view from one corner thereof;

FIG. 3 is a plan view thereof;

FIG. 4 is a front view thereof; and

FIG. 5 is a rear view thereof.

I claim:

The ornamental design for a retail food market, substantially as shown.
